LUGGAGE FRAME HAVING LOCKING HINGE STRUCTURE

Original Filed July 20, 1945

by Hill, Sherman, Mason, Cross ~~and~~ Company, 175

UNITED STATES PATENT OFFICE

2,666,227

LUGGAGE FRAME HAVING LOCKING
HINGE STRUCTURE

Leo Stein, Chicago, Ill.

Original application July 20, 1945, Serial No.
606,084. Divided and this application March
17, 1951, Serial No. 216,175

4 Claims. (Cl. 16—145)

1

The present invention relates to improvements in luggage frames and more particularly relates to such frames having improved hinge structure connecting two similar frame members together for swinging into open or closed relative positions.

This application is a division of my application Serial No. 606,084, filed July 20, 1945, Patent No. 2,545,501, dated March 20, 1951.

An important object of the present invention is to provide improved luggage frame structure wherein a pair of frame members are pivotally connected in such a manner as to swing readily into open or closed positions, with means holding the frame members open when they have been swung to the wide open position.

Another object of the invention is to provide improved means in a luggage frame hinge structure for retaining the frame members yieldably in one relative position.

A further object of the invention is to provide an improved luggage frame structure having means for automatically retaining the frame members in wide open position as an incident to swinging the frame members to such open position.

Still another object of the invention is to provide improved yieldable hinge locking means for luggage frames.

Other objects, features and advantages of the present invention will be readily apparent from the following detailed description of a preferred embodiment thereof, taken in conjunction with the accompanying drawing, in which:

Figure 1 is a perspective view of one type of luggage to which the present invention may be applied, showing a frame embodying the features of the present invention;

Figure 2 is a side elevational view of a luggage frame embodying the invention;

Figure 3 is an enlarged elevational view looking toward the inner side of the left hand luggage frame hinge structure as viewed in Figure 2 and taken substantially in the plane of line III—III;

Figure 4 is an outside elevational view of the left hand hinge structure of Figure 2 looking substantially in the direction of the arrows on the line IV—IV; and

Figure 5 is a view looking toward the right side of the structure shown in Figure 4, substantially as indicated by the line V—V with the exception, however, that the hinged frame structure has been swung open as indicated in dash outline in Figure 4.

Figure 6 is a plan view of the bag frame as shown in Figure 4, with the frame members in an extended position;

2

Figure 7 is a plan view of the device as shown in Figure 4, with the frame members extended and in the process of being unlocked.

In Figure 1 is shown, by way of example, a bag 10 in the form of a brief case having the usual side wall structure and expandible gussets 11 connecting the same at the ends and bottom while a luggage frame 12 is carried by the upper edges of the side walls and gussets.

For details of the luggage frame 12 reference is invited to my application above-identified and to my Patent 2,200,972, dated May 14, 1940. Suffice it here to say that the frame comprises a pair of complementary, fairly rigid, generally inverted U-shaped members 13 and 14. The frame members are arranged to be releasably locked by mechanism 15 (Fig. 2) including a carrying handle 17. The upper locking mechanism 15 may be of the kind to which the above-men-

tioned application is more particularly directed.

At the lower ends of the downturned arms or legs of the frame members 13 and 14, they are pivotally connected together by combination hinge and yieldable locking means preferably in the form of substantially identical combination hinge and locking devices 18, and it is to this structure that the present application is especially directed.

Each of the hinge-lock structures 18 comprises a hinge plate 19 which is attached to the bag material at the corners of the bag opening and to which the adjacent ends of the frame members 13 and 14 are similarly loosely pivoted by means of respective rivets 20 and 21 (Figs. 3 and 4). By preference the pivoting of the frame members 13 and 14 on the hinge plates 19 is in side-by-side relation so that each of the frame members is independently pivoted but in such relation that in the juxtaposed or closed condition of the luggage frame the frame members 13 and 14 will be reasonably snugly mutually engaged.

In order to facilitate swinging open of the frame members 13 and 14, the lower companion extremities of the frame members are preferably arcuately formed as indicated at 22. Thereby when the frame members 13 and 14 are swung open to a position as indicated in dash outline in Fig. 4, the arcuate extremity portions 22 can ride on one another or at least clear one another without interference until the frame has been swung to the fully open position as shown. In this fully open position, limit upon further opening is preferably accomplished by respective terminal shoulders 23 formed at the outer sides of the extremities of the frame members and which

in the fully open position of the frame members abut one another and lock the frame members against further opening movement.

In order to relieve the rivets 20 and 21 of shear stresses imposed thereon by the frame members 13 and 14 in the fully open position and wherein the limit shoulders 23 thrust against one another, the hinge plate 19 is provided with respective limit shoulders 24 at its opposite sides against which the frame members bear in the fully open position. By preference, the hinge plate limit shoulders 24 are provided at the upper ends of an inturned flange 25 on the margin of the plate. It will be observed that the shoulder termini of the marginal flange 25 terminate below an upper hinge portion of the plate 19 so as to afford clearance for swinging of the frame members 13 and 14.

For locking the frame 12, and thereby the bag 10 to which it is attached, in open position, means are provided whereby when the frame members 13 and 14 have been swung to wide open position, a locking mechanism automatically comes into operation to hold the frame in the open condition until intentionally manually released for closing. To this end, the mechanism 18 includes a locking cam plate 27 fixedly secured to one of the frame members, as for example the frame member 13 as by means of a pair of screws 28. While the hinge plate 19 is preferably carried by the outer sides of the frame members 13 and 14, the locking plate 27 is preferably carried at the inner sides of the extremity portions of the frame members. The locking plate 27 is constructed and arranged to extend substantially beyond the end of the attached leg of the frame member 13 and to overlap and project both laterally and endwise beyond the adjacent extremity portion of the frame member 14. As the frame member 13 is rotated or swung between closed and open positions, the locking plate 27 swings with it.

For effecting a connection of the plate 27 with the frame member 14, the pivot rivet 21 extends through an arcuate slot 29 in the plate 27 through which the shank of the rivet slides as the plate swings with the frame member 13 or when the frame member 14 is moved relative to the frame member 13, while the head of the rivet 21 maintains a loose connection of the locking plate and the frame member 14.

For locking purposes, the plate 27 has a locking shoulder 30 thereon behind which the frame member 14 is adapted to spring in the fully open relative positions of the frame members, substantially as shown in dash outline in Fig. 4 and in full outline in Fig. 5. To facilitate sliding of the plate 27 past the frame member 14 toward the locked condition, the outer face of the plate 27 is provided with a cam surface 31 leading to the shoulder 30 and opposing the frame member 14 in the range of relative opposition from the fully closed condition of the frame members to the fully open position of the frame members.

In the opening relative movement of the frame members 13 and 14, the frame members pivot about their respective pivots 20 and 21, the locking plate 27 swings with the frame member 13 and relative to the frame member 14, with the tapered cam surface 31 sliding along the opposing face of the frame member 14 until in the fully open position of the frame members, the frame member 14 snaps in back of the shoulder 30 on the plate 27. In the assembly, the pivot pin or rivet 21 is sufficiently longer in the shank

portion thereof than the thickness of the members through which it passes to afford some end play or looseness to avoid binding of the plate 27 and the frame member 14. This facilitates the springing of the cam locking plate 27 and the frame member 14 relatively to effect the interlocked open condition.

As may be seen from a consideration from Figures 4, 5, 6 and 7, when the frame members 13 and 14 are opened to their fully extended position the natural rigidity of the frame member 14 will maintain the bent-over ends of the frame in substantially parallel position and hence the frame 14 will not pass back over the shoulder 30 without outside aid. However, since the pivot pin 21 is somewhat longer than the combined widths of the plate 27 and the frame member 14 when these two parts are positioned in the fully extended position shown in Figure 5, the frame member 14 may be sprung laterally as shown in Figure 7. When thus sprung in the direction of the arrow as shown in Figure 7, the frame member 14 will clear the shoulder 30 to permit the frame members 13 and 14 to be collapsed into a closed position as shown in Figures 1, 2 and 3.

It has been found that the natural resiliency of the frame members 14 will permit the necessary springing thereof at both sides of the bag simultaneously when locking plates are to be utilized at both ends of the bag. Further, the natural resiliency of the frame members 14, in combination with the looseness of the pivot pin 21 will permit the members 13 and 14 to collapse, springing around the shoulders 30 when a relatively heavy closing pressure is manually exerted on the side frames 13 and 14.

It will be understood that either one or both of the hinge devices 18 may be provided with one of the locking plates 27. In the frame assembly as shown in Fig. 2, both of the devices 18 are shown as equipped with one of the locking plates 27. For uniformity in operation, the locking plates 18 are preferably secured to the same frame member, namely the frame member 13.

For additional firmness in the open condition of the luggage frame, the length of the arcuate slot 29 and the plate 27 may be such that the rivet 21 will engage the wall defining one extremity of the slot in the fully open condition of the frame as shown in Fig. 4, thus supplementing the thrust shoulders 23 and the retaining shoulders 24.

It will be understood that modifications and variations may be effected without departing from the scope of the novel concepts of the present invention.

I claim as my invention:

1. In a luggage frame assembly, a pair of frame members, a hinged plate for securing said frame members together, first pivot means securing one of said frame members to said hinge plate, second pivot means securing the other of said frame members to said plate whereby said frame members are rotatable on said pivots into an extended position or a closed position in which they lie immediately adjacent each other in substantially parallel relationship, a locking plate fixedly secured to said one frame member and extending beyond the end thereof into overlapping relation with said other frame member, said locking plate lying in a plane generally parallel to the plane of said hinge plate and having an interference shoulder thereon adapted to spring over the edge of said other frame member when the frame

members are in extended position, said second pivot being axially loose whereby said other frame member may be sprung relative to the locking plate to clear said shoulder and thereby permit movement of said frame members into said closed position.

2. In combination in a luggage frame assembly, a hinge plate having a pair of frames pivotally mounted thereon for movement between a closed position in which said frames are substantially parallel to each other into an open position in which the frames are in extended relation with each other, a locking plate fixedly secured to one of said frames and extending therebeyond into overlapping relation with the other frame, the pivot means supporting said other frame on said plate being axially loose whereby said other frame may be readily sprung laterally along said pivot relative to said locking plate, and laterally extending shoulder means on said locking plate for extension into the path of movement of said other frame to maintain said frames in an extended position when placed in such a position.

3. In combination in a luggage frame assembly of the character described, a pair of frame members, one of said frame members having on the pivotally mounted extremity portion thereof a locking plate projecting beyond the extremity and overlapping the extremity of the other frame member, shoulder locking means on the locking plate for cooperation with the extremity of the other frame member, the pivotal connection of said other frame member to said means having looseness axially of the pivot whereby said other frame member may be deflected relative to said one frame member and said locking plate to permit its pivotal movement past said locking shoulder.

4. In a luggage frame assembly, a pair of frame members having extremity portions, means pivotally connecting said frame extremity portions, a locking plate fixedly carried by an extremity portion of one of said frame members, and overlapping an extremity portion of the other of said frame members, said locking plate having a shoulder therearound interengageable with said other frame member extremity portion when said frame members are in extended position relative to each other, an inclined cam surface connecting the portion of said locking plate immediately adjacent said one frame member to said locking shoulder whereby movement of said frame members into extended position will cause said other frame member extremity portion to be deflected by said cam surface over said shoulder, the pivot means of said other frame extremity portion being axially loose whereby said other frame extremity portion may be deflected readily relative to said one frame extremity portion and said locking plate to thereby permit said other frame member extremity portion to pass back over said locking shoulder into close side by side relationship with said one frame member.

LEO STEIN.
